(57) **CLAIM**

The ornamental design for a dryer bar, as shown and described.

DESCRIPTION

FIG. 1 is a front perspective view of a dryer bar showing our new design;

FIG. 2 is a front view thereof, the rear view being a mirror image thereof;

FIG. 3 is a top view thereof;

FIG. 4 is a bottom view thereof; and,

FIG. 5 is a left side view thereof, the right side view being a mirror image thereof.

The broken line showing of a surface pattern in FIGS. 1-3 and 5 is included for the purpose of showing environmental portions of the dryer bar and forms no part of the claimed design.
